(57) **CLAIM**

The ornamental design for a corner table for an airplane, as shown and described.

DESCRIPTION

FIG. 1 is a perspective view of the inventive corner table for an airplane;

FIG. 2 is a top plan view of the corner table for an airplane; and,

FIG. 3 is a front plan view of the corner table for an airplane. The broken lines are for environmental purposes only and form no part of the claimed design.
